CLAIM

The ornamental design for a face mask retention clip for releasably fastening to apparel, as shown and described.

DESCRIPTION

FIG. 1 is a perspective view of a face mask retention clip; FIG. 2 is a front view of the face mask retention clip; FIG. 3 is a rear view of the face mask retention clip; FIG. 4 is a left view of the face mask retention clip; FIG. 5 is a right view of the face mask retention clip; FIG. 6 is a top view of the face mask retention clip; FIG. 7 is a bottom view of a face mask retention clip; FIG. 8 is a top view of inside of a lock side of the face mask retention clip; FIG. 9 is a bottom view of inside of a pin side of the face mask retention clip; FIG. 10 is a side view of the face mask retention clip with the pin side separated from the lock side; and, FIG. 11 is an example use case for the face mask retention clip releasably fixed to a baseball style cap. The broken lines in the drawings are presented for illustrative purposes only and form no part of the claimed design.
